UNITED STATES PATENT OFFICE

2,519,120

AIR-CONDITIONING SYSTEM

Charles E. Davis, Lake Orion, Mich.

Application May 28, 1948, Serial No. 29,873

5 Claims. (Cl. 219—39)

1

This invention relates to new and useful improvements in air conditioning systems and the primary object of the present invention is to provide a novel and improved structure for controlling the temperature of various rooms of a building in a very convenient manner.

Another important object of the present invention is to provide an air conditioning system including an air delivery housing and novel and improved means for selectively introducing warm or cool air into the delivery housing.

Another object of the present invention is to provide an air conditioning system including a radiator housing having a plurality of louvers and means responsive to heat within the housing for actuating the louvers to deflect or direct air therefrom.

Another object of the present invention is to provide an air conditioning system including a plurality of refrigerant holding coils and novel and improved means for directing air over the coils to a discharge area.

Another object of the present invention is to provide an air conditioning system including a radiator housing, a group of liquid holding coils mounted in the housing and novel and improved means for heating the liquid in said coils.

A further object of the present invention is to provide a device for conditioning air that is extremely small and compact in structure and which may be quickly and readily installed in a building structure to function efficiently for either heating or cooling a room or a group of rooms.

A still further aim of the present invention is to provide a device for conditioning air that is simple and practical in construction, strong and reliable in use, neat and attractive in appearance, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a fragmentary perspective view of a building structure and showing the present invention applied thereto, and with parts of the present invention broken away and shown in section;

Figure 2 is an enlarged sectional view taken substantially in the direction of section line 2—2 of Figure 1;

Figure 3 is a front elevational view of the radiator housing used in conjunction with the present invention;

Figure 4 is a longitudinal vertical sectional view taken substantially on the plane of section line 4—4 of Figure 2;

Figure 5 is a sectional view taken substantially

2

on the plane of section line 5—5 of Figure 1, and;

Figure 6 is a diagrammatic view showing the circuit system used in conjunction with the present invention.

Referring now to the drawings in detail, where-in for the purpose of illustration, there is disclosed a preferred embodiment of the present invention, the numeral 10 represents a radiator shield or housing in which there is suitably mounted a radiator 12 having an upper chamber 14, side chambers 15, a lower chamber 16 and a plurality of coils or connecting pipes 18 between the upper and lower chambers 14 and 16. Supported by a bracket 20 which is disposed within the lower chamber 16, is a conventional electrical heating unit 22 which is provided with a well-known thermostatic switch 24. Connected to the lower chamber 16 of the radiator 12, is an inlet pipe 26 that is provided with a manually operated valve 28 for controlling the amount of liquid that enters the chamber 16. Extending from the upper chamber 14 and communicating with the lower chamber 16, is a pair of return pipes 30 and 32.

The forward wall 34 of the housing 10 is provided with an opening 36 having a plurality of spaced parallel, horizontally disposed pivot bars 38 that pivotally support louvers or baffle strips 40, the inner ends of which are connected by a wire or actuating cord 42.

Mounted within the housing, is a conventional thermostatic control 44 having a heat responsive ring 46 and an actuating arm 48 which is connected to the cord 42. As the air within the radiator housing 10 remains in a warm state, the arm 48 is in a lowered position and the baffle strips 40 are opened to permit warm air to pass outwardly from the housing 12. However, when the air within the housing 12 reaches a predetermined low temperature, the arm 48 will be raised to pivot the baffle strips 40 to a closed position.

The numeral 50 represents a fan housing having a slidable door 52 and an opening 54 in its lower wall. Fixed to the lower wall of the fan housing 50, is a liquid receiving chamber or container 56 having a drain plug 58. Loosely mounted within the container 56, is a coiled tube 60 having an inlet end 62 and an outlet end 64 which are connected to a suitable source of refrigerant solution.

Fixed to the container 56 and positioned within the housing 50, is a mounting 66 that supports a preferably electrical motor or fan 68 having a fan blade 70. Entering the housing 50, at one end of a liquid pipe (not shown) is a delivery nozzle 72 supplying liquid such as water to the container 56. This nozzle 72 is provided with a conventional float valve mechanism 74 which will cut off the supply of liquid through the nozzle 72 at a predetermined depth in the container in order

to prevent liquid from passing outwardly from the housing 50 when the door 52 is opened.

In practical use of the present invention, the fan housing 50 is connected to and communicates with a plurality of conduits or air ducts 76 which are preferably disposed between the floor joists 78 of a building structure 80. These air ducts 76 communicate with one or more radiator housings 10, so that a flow of air will be forced through the ducts 76 by the fan 70, into the housing or housings 10 and outwardly through the openings 36 in the said housing. One of the ducts 76 is connected to an open grill 82 that is positioned on the floor of the structure 80 or on the baseboard of the room in which the radiator housings 10 are disposed.

It is preferred that the motor 68 be connected directly to a pair of circuit lines 86 by conductive wires 88 having a switch 90, and that the lines 86 be connected to each of the heating units 22. A switch 92 is provided for each of the heating units so that the same may be controlled independently of each other.

For heating of a room, the refrigerant solution is first removed from the coils 60, the heating coils 22 are energized, and the motor 68 actuated to direct a flow of air over the heated coils or pipes 80, which air will pass through the opening 36 in the housing 10. When the temperature of the air leaving the housing 10 reaches a predetermined low temperature, the thermostat 44 will be actuated to close the louvers 40 thus preventing air in the room from entering the housing 10 when the switch 90 is activated to open the circuit to the fan. The air in the room will in this manner remain in a substantially constant temperature during use of the present heating system. The water or suitable liquid that is placed in the container 56 evaporates and is drawn by the fan blade 70 into and through the conduit 76 and housing 10 to properly moisturize the air entering the room.

To reduce the temperature of a room, the heating units 22 are de-energized and the fan actuated to direct a flow of cool air through the conduit 76 and outwardly from the opening 36 in the housing 10.

To further reduce the temperature of a room, the refrigerant solution is placed in the pipes 62 and 64 to retain the coils 60 in a cold state, so that the air directed by the motor 68 and fan blade 70 will be relatively low in temperature. Obviously, the system shown in the drawings may be applied to a plurality of rooms of a house using any suitable number of radiator housings and heating coils to effectively and efficiently heat the room and which will also cool the room when such is desired.

In view of the foregoing description taken in conjunction with the accompanying drawings it is believed that a clear understanding of the construction, operation and advantages of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention what is claimed as new is:

1. An air conditioning system for building structures comprising a group of radiator housings,

ings, liquid holding coils mounted in each of said housings, means for heating liquid in said coils, louvers adjustably carried by each of said housings, means for directing a flow of air over the liquid holding coils, and means responsive to heat within the housings for actuating said louvers into and out of an open position, said means for directing a flow of air over the liquid holding coils comprising a fan housing and a group of air ducts extending between said radiator housings and said fan housing.

2. An air conditioning system for building structures comprising a group of radiator housings, liquid holding coils mounted in each of said housings, louvers adjustably carried by said housings, means responsive to heat within the housings for regulating the louvers of each housing, a fan housing, air ducts connecting said fan housing to each of said radiator housings, means for introducing a moisture to air within the fan housing, and switch means for controlling said heating means.

3. The combination of claim 2 wherein said means for introducing a moisture to air within the fan housing includes a liquid container communicating with the fan housing and forming the lower portion of the fan housing, and a fan mounted in said housing for directing a flow of air into the air ducts.

4. An air conditioning system for building structures comprising a group of radiator housings mounted in selected rooms of a building structure, liquid holding coils mounted in each of the radiator housings, an electrical heating unit disposed within each radiator housing for heating the coils of each radiator, a thermostatic switch for each of the heating units, said thermostatic switches being mounted within the radiator housings, each of said radiator housings having openings therein, louvers carried by each of said radiator housings and in registry with said openings, heat responsive members disposed within said radiator housings and connected to the louvers for actuating the latter, a fan housing disposed remotely from the radiator housings, air ducts extending from the fan housing and leading to the radiator housings, a fan mounted in the fan housing for impelling air through the ducts and into the radiator housings, a liquid holding receptacle mounted on said fan housing, means for introducing a liquid into the receptacle, a valve controlling the supply of liquid to the receptacle, and a float responsive to the level of a liquid in the receptacle for actuating the valve.

5. The combination of claim 4 and a floor grille, and a further air duct extending from the floor grille and leading to the fan housing, said further air duct having an outlet entering the fan housing beneath the fan for use of the fan in sucking air through the further air duct.

CHARLES E. DAVIS.
